UNITED STATES PATENT OFFICE

KARL A. MAYR, OF CHICAGO, ILLINOIS

FURNACE

Application filed February 26, 1927. Serial No. 171,146.

The present invention relates to improvements in furnaces, and in particular, furnaces for heating coils or tubes, such as water heater coils or steam generator coils.

3 An important object of the invention resides in the provision of a new and improved furnace in which there will be efficient and complete combustion of fuel.

Another object is to provide a novel furnace in which the fuel and the combustion air are delivered to the combustion chamber in a manner such that a homogeneous fuel mixture is quickly obtained, in which a high ignition temperature is maintained, and in 15 which a long flame travel is provided.

A further object is to provide a new and improved furnace which is compact, and in which oil or powdered coal can be efficiently consumed, thereby adapting the furnace to 20 serve steam generators of various types in steam locomotives or cars.

Another object resides in provision of means for keeping the inside of the fire walls at a low temperature.

25 Still another object is to provide a novel furnace in which the incoming combustion air cools the walls of the combustion zone; in which the incoming combustion air is pre-heated by passing over, and hence cooling, 30 the outer walls of the combustion chamber, and by absorbing heat from the waste products of combustion in a heat exchanger; and in which the heating coils for absorbing the heat of combustion are arranged to cool the 35 inner surfaces of the furnace walls.

A more specific object resides in the provision of a novel furnace in which the combustion chamber is divided into two inter-communicating parts by an upstanding partition, and in which one side of the partition is cooled by incoming combustion air and the other side is cooled by proximity of the heating coils.

40 Further objects and advantages will become apparent as the description proceeds.

Figure 1 is a longitudinal vertical sectional view taken along line 1—1 of Fig. 2 of a furnace embodying the features of my 45 invention.

Fig. 2 is a transverse vertical sectional view taken along line 2—2 of Fig. 1.

Fig. 3 is a fragmentary view of one side of the front end of the furnace.

Fig. 4 is a horizontal sectional view taken 55 along line 4—4 of Fig. 1.

Fig. 5 is a vertical sectional view taken along line 5—5 of Fig. 2.

Fig. 6 is a plan view on a reduced scale.

Fig. 7 is a horizontal sectional view taken 60 along line 7—7 of Fig. 1.

Fig. 8 is a fragmentary bottom view of the furnace.

Fig. 9 is a fragmentary sectional view of a 65 modification, the view being taken in the same plane as Fig. 1.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring to the exemplary embodiment of the invention, the furnace comprises a combustion chamber 10 of a suitable shape having bottom, front, top, rear and side fire walls 11 to 15, respectively. The front wall 12 comprises a section 16 which is inset and which is inclined upwardly and rearwardly. These walls may be constructed or made of any suitable material adapted to withstand high temperatures. In the present instance, the bottom, front and top walls, since they are exposed to the highest temperatures, are constructed out of refractory material; and the rear and side walls, since they are cooled as will be hereinafter described, are constructed preferably out of metal, such as cast iron or a chromium alloy.

95 The combustion chamber 10 is formed with two main chambers 10^a and 10^b which are separated by a vertical partition 17 rising from the bottom wall 11, and which communicate over the partition. Preferably, the partition 17 rises to a level with the lower 100

edge of the front wall section 16. The front surface of the partition 17 is inclined at a slight angle upwardly and rearwardly. The front combustion chamber 10^a is designed to produce and maintain a high ignition temperature for the fuel regardless of the amount of fuel consumed and of load variations; and the chamber 10^b is provided mainly to provide the necessary space to secure complete combustion of the fuel at high loads.

Any suitable fuel, such as oil or coal, may be burned in the furnace. Preferably, powdered coal is delivered by a suitable coal feeder 18 from a suitable coal bunker or hopper 19 through a spout 20 into the chamber 10^a. The hopper 19 rests against the front wall section 16. The fuel enters the front of the chamber 10^a at a point approximately two-thirds of the total height of the chamber above the bottom wall 11, and falls downwardly into the combustion zone.

Combustion air is supplied to the chamber 10^a below the spout 20 through a plurality of spaced ports 21 in the front wall 12 from an air chamber 22 built on the outside of the wall. The ports 21 are spaced substantially over the entire area of the lower section of the wall 12, and open laterally of the wall into the chamber 10^a. Incoming air serves to keep the wall 12 relatively cool. Secondary combustion air is supplied to the rear of the combustion chamber 10^a through a plurality of ports 23 from an air chamber 24 in the partition 17. The ports 23 open at and are spaced substantially over the entire area of the front surface of the partition 17. Incoming air serves to keep the front surface of the partition 17 relatively cool. Opposite sides of the air chambers 22 and 24 are connected by suitable air ducts 25. In the present instance, these ducts are formed in lower refractory sections 15^a of the side walls 15.

As the powdered coal falls from the spout 20 into the chamber 10^a, it mixes with the combustion air, and starts to burn. The incoming jets of air from the ports 21 attack the downwardly directed flame and fuel mixture, and turn or deflect them to the rear. The incoming jets of air from the ports 23 then attack the flame, and turn or deflect it upwardly to sweep over the upper edge of the partition 17 downwardly into the chamber 10^b. By admitting a large number of jets of air distributed over a large area into the chamber 10^a, and by so introducing the fuel with reference to the air jets as to cause a swirling motion of the combustible mixture in the combustion zone, a homogeneous mixture is obtained, and quick and efficient combustion results. The incoming fuel is immediately subjected to heat radiated from the upwardly traveling products of combustion, and heat reflected from the front inclined surface of the partition 17. The construction 65 provides a long flame travel so that if the com-

bustion is not completed in the chamber 10^a, it will be completed in the chamber 10^b.

The products of combustion may be directed from the furnace through any suitable path, and preferably in a manner to permit removing most of the heat in said waste products. In the present instance the gases pass from the chamber 10^b through an opening 26 in the lower part of the rear wall 14, and then upwardly through a chamber 27 at the rear end of the furnace. From there, the gases split, and pass in two portions through two horizontal and preferably rectangular chambers 28 extending along opposite sides of the chamber 10 to the front of the furnace. From the front ends of the chambers 28, the gases pass upwardly through two chambers 29, then through a plurality of closely spaced tubes or flues 30 extending longitudinally through a pair of chambers 31, and then through a chamber 32 overlying the chamber 27 into a suitable stack 33. A fan 34 may be provided to create a forced draft.

The walls of the chambers 27, 28 and 30, preferably, are constructed out of ordinary steel or chromium steel plates. The structures of the chambers 28 rest on suitable supporting means projecting outwardly from the side wall sections 15^a. Preferably these supporting means take the form of ledges comprising a plurality of floor plates 35 resting on channel frameworks 36.

An outer furnace wall 37 of suitable heat insulating material encloses the top, rear and sides of the furnace, and provides a narrow air space 38 over the top wall 13, a narrow rear air space 39, and narrow side air spaces 40. These air spaces intercommunicate, and open into the rear ends of the air chambers 31. The lower end of the rear air space 39 opens to the atmosphere through ports 41 (see Fig. 8). The side spaces 40 open to the atmosphere at the front and through a plurality of ports 42 (see Fig. 8) in the plates 35 at the bottom. The front ends of the chambers 31 open through air ducts or passages 43 to the chamber 22. Combustion air thus passes through the spaces 39 and 40, then through the chambers 31, and then through the ducts 43 to the chamber 22, and in so doing the outside walls of the chambers 27 and 28, the inside walls 15 of the chambers 31, the top wall 13, and the products of combustion passing through the tubes 30 are cooled. As a result, the combustion air is preheated, and the chimney gases are relatively cool.

Due to the reduced velocity of the gases of combustion in the chamber 10^b, the ashes fall to the bottom. The lower wall 11 of the chamber 10^b is inclined upwardly from each side to the center so as to cause the ashes to gather at the sides from where the ashes can be easily removed through suitable clean-out doors 44.

Pipe or tube coils 45 adapted to have water

130

or other fluids circulated therethrough are arranged in a suitable manner next to the inner surfaces of the walls 11, 13, 14 and 15, and next to the rear surface of the partition 17. These coils may comprise one or more tube lines. Each line is wound in a series of substantially vertical laterally disposed loops, first about the chamber 10^a, and then about the chamber 10^b, and then in series of inclined loops downwardly about the nest of tubes in the chamber 10^b. In the present instance, I have provided three tube lines 46, 47 and 48. These lines are arranged in parallel so as to permit the liquid to flow therethrough with a velocity most favorable to heat transmission, and so as to reduce the length of flow of the liquid to reduce friction losses. Flow through the fluid lines may be in either direction to secure a counterflow or a parallel flow. Preferably I have arranged the tubes to secure a parallel flow with the products of combustion since this arrangement results in cooler tubes and best serves heavy load fluctuations. The inlet ends of the tube lines extend through suitable openings (not shown), in the walls of the furnace, and are adapted to be connected in any suitable system utilizing the heated liquid or vapor leaving the coils 45. The lower sides of the loops in the chamber 10^b are arranged in sets of three superimposed in a vertical plane, so as to provide a series of spaces 50 adapted to permit the ashes to fall to the bottom wall 11 in the chamber 10^b. A similar construction (see Fig. 9) may be employed in the chamber 10^a, in which event said chamber is provided with clean-out doors 51. The loops are arranged in close relation so as to substantially cover the surfaces referred to, and do not obstruct the interior of the chamber 10. The liquid in the coils 45 thus serves to cool the surfaces.

The heat of combustion may be utilized for a large variety of purposes. Thus, the coils 45 may be water heater coils or may be steam generator coils. In the present instance, the coils 45 form part of a steam generator. It is to be understood that the specific type of steam generator involved is immaterial.

The ends of the tube lines 46, 47 and 48 project through the opening 26 in the rear wall of the chamber 10, and are connected respectively to three nests of steam superheater coils 52, 53 and 54. The steam superheater coils 52 span the upper end of the chamber 27 and rest at their ends on the supports 35. The steam superheater coils 53 and 54 are respectively positioned in the chambers 28.

It will be evident that I have provided a construction in which the walls of the furnace chamber are cooled on the inside by the coils provided to absorb the heat of combustion, and on the outside by incoming air of combustion. Waste heat in the products

of combustion is utilized to preheat the combustion air and to superheat the steam passing through the superheater coils 52 to 54 inclusive. The furnace is extremely compact and is especially adapted for use in steam locomotives or steam cars. By preheating the air of combustion, by obtaining a homogeneous fuel mixture in the combustion chamber 10^a, and by providing a long flame travel, extremely efficient combustion results.

I claim as my invention:

1. A furnace having, in combination, an inverted U-shaped combustion chamber, means for admitting fuel in the upper front part of said chamber and in a downward direction, means for admitting air to the front and rear sides of the front section of said chamber, said means being distributed over substantial portions of said sides and means for drawing off the products of combustion from the lower end of the rear section of said chamber.

2. A furnace having, in combination, a combustion chamber, a transverse upstanding partition wall dividing said chamber into front and rear chambers communicating at their upper ends, the front side of said wall being straight and inclined upwardly and rearwardly, said partition wall being formed with an inner air chamber, and with a plurality of air ports opening from said air chamber into said front combustion chamber, and means for delivering fuel into the front and near the top of said front combustion chamber, and in a generally downward direction.

3. A furnace having, in combination, a combustion chamber, an upstanding partition wall dividing said chamber into front and rear chambers communicating over said wall, the front wall of said front chamber being formed with an upper offset and rearwardly inclined section, means at the base of said section for discharging fuel downwardly into said front chamber, the front surface of said partition wall being inclined upwardly and rearwardly, an air chamber formed in said front wall below said section, a plurality of ports opening from said air chamber through said front wall to said front chamber, an air chamber formed in said partition wall, and a plurality of ports opening from said last mentioned air chamber to said front chamber.

4. A furnace having, in combination, a combustion chamber, means for admitting fuel to said chamber, means for admitting air to said chamber and a plurality of cooling pipes adapted to have a fluid circulated therethrough wound in closely spaced loops about said chamber to cover the side, top and bottom fire walls, said loops being grouped at their bottom, the bottom lengths of the members of each group being superimposed in a vertical plane to provide spaces for permitting ashes to fall to the floor of the chamber.

5. A furnace having, in combination, a

combustion chamber, a vertical upstanding partition in said chamber dividing said chamber into front and rear sections, means for delivering fuel to said front section, air ports in the front side of said partition for delivering combustion air to said front section, said side being uncovered by pipes, and a plurality of closely spaced pipes positioned next to the inner surfaces of said chamber and the rear side of said partition.

6. A furnace having, in combination, a combustion chamber, a vertical upstanding partition in said chamber dividing said chamber into front and rear sections, means for delivering fuel to said front section, air ports in the front side of said partition and opening to said front section, a plurality of pipes wound about the inner surfaces of said chamber and over the rear side of said partition, means for conducting air over the outer surfaces of the walls of said combustion chamber to said ports, heat exchange means positioned adjacent and along the outside of the walls of said chamber for transferring heat from the products of combustion to said air, and means for directing the products of combustion to said heat exchange means.

7. A furnace having, in combination, a chamber, a central partition dividing the chamber into front and rear chambers, means for admitting fuel to said front chamber, means for admitting air to said front chamber, steam generating pipes positioned in closely spaced relation over the inner surfaces of certain of the walls of said chambers, superheaters positioned horizontally along the outer sides of the walls of said chamber, heat exchange means positioned along the outer sides of said chamber and over said superheaters, means for directing waste gases from said combustion chamber through said superheaters and then through said heat exchange means, an outer wall enclosing said furnace, and defining an air space about the walls of said chamber, and means for directing air from said space through said heat exchange means to said air admitting means.

8. A furnace having, in combination, a combustion chamber, an upstanding partition wall dividing said chamber into front and rear chambers communicating over said wall, means for delivering fuel into said front chamber, an air chamber formed in the front wall of said front chamber, a plurality of ports opening from said air chamber through said front wall to said front chamber, an air chamber formed in said partition wall, and a plurality of ports opening from said last mentioned air chamber to said front chamber.

9. A steam generator comprising, in combination, a combustion chamber, a partition wall dividing said chamber into two sections, one section being larger than the other, fuel and air supply means discharging into the

larger section, water and steam carrying tube coils, said coils constituting a substantial portion of the walls of said sections, and ash discharge means at the bottom of the smaller section, said ash discharge means being accessible from both sides, and comprising a floor sloping downwardly toward each side.

10. A steam generator comprising, in combination, a combustion chamber, an upstanding partition dividing said chamber into two sections, one section being larger than the other, fuel and air supply means for discharging into the larger section, convection chambers located alongside said combustion chamber, water and steam coils in said combustion chamber, said coils constituting a substantial portion of the walls of said combustion chamber, and also constituting the inner walls of said convection chambers.

11. A steam generator comprising, in combination, a furnace, a partition dividing said furnace into front and rear chambers, means for supplying fuel and air to one of said chambers, means for removing ashes from the bottom of the other of said chambers, a convection chamber located outside and along the end wall of said second chamber, an opening formed in the lower part of said end wall for connecting said second chamber to said convection chamber, the bottom wall of said convection chamber being inclined toward the bottom of said second chamber, and heat absorbing tubes located in the upper part of said convection chamber, the lower part of said convection chamber being unobstructed.

In testimony whereof, I have hereunto affixed my signature.
